UNITED STATES PATENT OFFICE.

PHILIP D. PARSONS, OF PHILADELPHIA, PENNSYLVANIA, ASSIGNOR TO SCOTT PAPER COMPANY, A CORPORATION OF PENNSYLVANIA.

DISPENSING MACHINE.

1,424,772.

Specification of Letters Patent. Patented Aug. 8, 1922.

Original application filed September 10, 1920, Serial No. 409,348. Divided and this application filed March 9, 1922. Serial No. 542,245.

To all whom it may concern:

Be it known that I, PHILIP D. PARSONS, a citizen of the United States, and resident of Philadelphia, county of Philadelphia, 5 State of Pennsylvania, have invented an Improvement in Dispensing Machines, of which the following is a specification.

My invention has for an object mechanism, preferably coin-controlled, for enabling paper towels and other articles, arranged within a cabinet, to be dispensed in regulated quantities; and in the preferred construction of the mechanism, I arrange the operative parts of such form and co- 10 operating in such manner that one or a plurality of coins may be deposited at a time and then the mechanism operated once for a single coin or repeatedly for as often as the number of coins deposited as the preliminary operation, the devices discharging 15 or delivering a towel or article with each operation.

My object is further to so construct the operating parts that they are few and 20 simple in structure and can readily be removed and replaced or substituted in part or in whole without the necessity of any tools.

With the above and other objects in view, 25 the nature of which will be more fully understood from the description hereinafter, the invention consists in the novel construction of dispensing machines, as hereinafter more fully described and defined in the 30 claims.

In the drawings: Fig. 1 is a front view of 35 a dispensing machine embodying my invention, having the upper portion broken away; Fig. 2 is a cross sectional view of the same taken on line 2-2 of Fig. 1; Fig. 40 3 is a sectional view, similar to Fig. 2, but with the coin-controlled mechanism shown at the completion of its discharging movement; Fig. 4 is a perspective view of the 45 coin-controlled mechanism separated from the case; and Fig. 5 is an end view of the ejector cylinder.

2 is the case and may be made of any shape desired, but in the particular example, 50 here shown, it is made rectangular in form and suitable for receiving a stack of folded paper towels 6, in any number desired, arranged one above the other and from which the lowermost towel is discharged at each

operation. The lower part of the case is 55 provided at its rear with an inwardly directed shelf 3 which preferably inclines upward and terminates in a beaded part 3^a which acts as a support for the towels near their middle and throughout their length, 60 the shelf insuring a firm support for as many towels in the stack as may be desired. The forward portion of the bottom part of the case is provided with a second inclined shelf 4 which extends backward 65 and downward and terminates in a beaded edge 5, said shelf 4 acting to support the stack of towels at their forward portions, but so as to permit one of the under flaps 8 of the lowermost towel to fall by gravity 70 and be sustained in position upon and so as to be received by the rotary ejector. The ejector comprises the cylindrical body 9 secured upon heads 13 fastened to the shaft 14 journaled in the casing, the said body 75 being slit along its length to form the outwardly extending jaw 11 and the inwardly bent flange 10 and providing between them the longitudinal throat 12 to receive the flap 8 of the towel when the ejector is rotated. 15 is a coil spring arranged about shaft 14, having one end connected with one 80 of the heads 13 of the ejector and the other end connected with the main case, so that normally the ejector is returned to the position shown in Fig. 2 with the jaw 11 resting 85 against the beaded edge 3^a of the shelf 3. The rotary ejector 9 is operated by the mechanism to be now described.

The end of the ejector shaft 14 is provided with a pinion 16. Meshing with the pinion 16 is a driving gear 17 provided with sufficient teeth to give the pinion and ejector approximately three-quarters of a revolution as a minimum. The driving gear 95 17 is provided with a wing nut 20 by which to rotate it and also has a coin slot 18 through it, providing a runway 36 for the coin deposited through the slot 19 in the front plate 126 of the case. Normally, the 100 slot in the gear 17 is inclined so that the coin will roll backward through the gear to a position in front of the pinion 16 and coin carrier gear 21, as indicated in dotted lines in Fig. 2. Coin carrying gear 21 is 105 provided with teeth engaging the pinion 16 and is driven by said pinion and hence rotates in the same direction as the operat-

ing or driving gear 17; it is journaled upon a stud 22 and has a slot 23 into which a fixed pin 24 extends to limit the extent of its rotary movements. This is not so material in the normal position because the jaw 11 of the ejector 9 acts to stop rotation of pinion 16 by contact with shelf 3 (Fig. 2), but in the ejecting movement (Fig. 3), it is important that the parts shall be arrested at the proper time and this is insured by contact of the end of slot 23 with the pin 24. The gear 21 is further provided with the coin stop 25, made in the form of a lateral flange against the end of which the coin rests, as shown in Fig. 2; and moreover, the lower portion of this gear is provided with the coin guide floor 34 upon which the coin rests, as indicated, said floor also providing a runway for coins or slugs of smaller diameter which may be inserted in the machine and whose presence are not intended to be capable of operating the mechanism. In case of the deposit of these smaller coins or slugs, they pass the gear 21 and leaving the runway thereof are received upon the guide 32 by which they are directed into the coin drawer 33, which has a portion divided off for receiving them.

Referring again to the coin carrier gear 21, it will be noted that in addition to the operating teeth 37 to insure its rotation, it has teeth 38 and 39 for operation respectively with the pawls 29 and 27 to insure complete or full rotary movement when a coin is in the custody of the gear 21 and to prevent movement when no coin is present. The pawls 27 and 29 are preferably pivoted upon the same stud 28 and are so arranged that when pawl 29 is down to engage the teeth 38, pawl 27 is held up clear of the teeth 39, and vice versa. It will further be noted that the gear 21 is provided with a high tooth 26 which normally holds the pawl 29 up (Fig. 2), the particular function of this being to also hold up the part 30 of this pawl to permit the coin to roll into position against the stop 25 and position itself under the said part 30 of the pawl. It will now be understood that when the gear 21 is rotated clockwise with the coin in position, the high tooth 26 releases the pawl 29 but part 30 thereof then rests upon the coin and hence cannot fall sufficiently to enable the pawl to engage the teeth 38. The discharging movement may therefore continue with the other pawl 27 engaging the teeth 39 of gear 21 and thus prevent its back movement while the coin is in transit. When the positions of the parts reach those indicated in Fig. 3, the coin is thrown onto the coin guide 31 of the case and by it guided down into the drawer 33. The discharge of the coin releases the pawl 29 and it falls into engagement with the teeth 38 and at the same time, by its

superior weight, lifts pawl 27 clear of the teeth 39 of gear 21 and permits it to rotate backward to its initial position (Fig. 2). It will be seen that the pawl 27 requires the ejecting movement to continue until completed and the coin deposited in drawer 33, so that only one towel will be delivered for one coin; and pawl 29 prevents the operation of the ejector if no coin has been deposited and retained against the stop 25. Should an attempt be made to eject a towel without depositing the coin, the high tooth 26 will be moved to allow the pawl 29 to engage the wide gap in the teeth 38 and prevent more than a very slight rotation of the 80 ejector cylinder; and when the handle 20 is released, the spring 15 returns the high tooth again under the pawl 29, as shown in Fig. 2, so that the parts are automatic.

There is room in gear 17 for two additional coins, so that three coins may be deposited, and in such event the handle 20 may be operated three times in succession, ejecting one towel at each operation.

A short bridge piece 35 is provided between the gears 17 and 21, to provide a runway for the coin from gear to gear. It will be seen that there are only four operative parts, and these are removably positioned; hence the device is exceedingly simple and not liable to become worn or get out of order. In case of breakage, repairs may readily be made by a person of ordinary intelligence. The coin operable parts are covered by an end plate 40 which may be locked or otherwise secured in position for permitting access when desired.

More particularly referring to the ejector operation, the forward rotation of the ejector receives the flap 8 of the towel in the 105 throat 12, causing it to be bent over the jaw 11 and pulled downward, which action continues to also pull down the body of the towel back of the front plate 4 to a position above the lower shelf 41 and practically releasing the towel from the rear shelf 3 also. The return of the ejector releases the towel and leaves the same in position on the shelf 41 to be removed by hand. When one towel is removed, the flap or tab 115 8 of the next lowermost towel falls by gravity to position shown in Fig. 2 and the operation may be repeated by deposition of or presence of another coin.

The mechanism is designed to operate for 120 any predetermined sized coin such as found in the United States and foreign countries, and the adjustment is made by cutting back the stop flange 25 of gear 21 to permit the coin to enter far enough to properly cooperate with the pawl part 30 and to be carried with the gear 21 when rotated.

The construction of my improved machine is such that the towels are inaccessible normally, and only one towel can be obtained 130

for one coin. It will be understood, however, that in those cases where the machine is installed and it is not desired that pay for the towels shall be exacted, the machine 5 may be employed for dispensing without coins by simply removing the pawls 29 and 27 or the gear 21 itself, if desired.

In this application no claim is made for the specific construction of coin controlled 10 lock, as the same forms subject matter of application Serial Number 409,348, filed September 10, 1920, of which this is a division.

It will now be apparent that I have devised a novel and useful construction which 15 embodies the features of advantage enumerated as desirable, and while I have in the present instance shown and described the preferred embodiment thereof which has 20 been found in practice to give satisfactory and reliable results, it is to be understood that I do not restrict myself to the details, as the same are susceptible of modification in various particulars without departing 25 from the spirit or scope of the invention.

Having now described my invention, what I claim as new and desire to secure by Letters Patent, is:—

1. In a dispensing cabinet, a case providing 30 a compartment having a shelf at the bottom and extending part way across from the rear to support articles such as paper towels, combined with a rotary ejector having a throat opening for receiving a tab of 35 the towels to be dispensed, hand operable means for imparting a rotary action to the ejector for the greater portion of a revolution, and a spring for returning the ejector

to initial position with its throat opening directed upward. 40

2. The invention according to claim 1, further having a front plate extending downward from the case to prevent access to the interior of the compartment above the ejector. 45

3. The invention according to claim 1, further provided with coin-controlled means for normally locking the hand operable means against operation, but releasing it when a coin is in position. 50

4. The invention according to claim 3, wherein the spring for returning the ejector to initial position also returns the coin-controlled means to initial position.

5. In a dispensing cabinet, a case having 55 an opening at the bottom and provided with supporting means for the articles to be dispensed, a rotary cylindrical ejector having a longitudinal throat opening provided with an extended jaw to one side thereof, hand 60 operable means to rotate the ejector, a spring to return the ejector to its initial position, and a shield extending downward from the case over the front and upper portion of the cylindrical ejector. 65

6. The invention according to claim 5, wherein the hand operable means comprises a pinion on the ejector axis and a large gear meshing therewith and provided with a handle part, and coin-controlled means for locking the handle and gear against movement except when a coin is present. 70

In testimony of which invention, I hereunto set my hand.

PHILIP D. PARSONS.
